UNITED STATES PATENT OFFICE.

JOHN H. BURKHOLDER, OF ASHLAND, OHIO, ASSIGNOR TO THE ELITE MANUFACTURING COMPANY, OF ASHLAND, OHIO, A PARTNERSHIP.

LIFT-JACK.

1,097,581.

Specification of Letters Patent. Patented May 19, 1914.

Application filed September 11, 1912. Serial No. 719,731.

To all whom it may concern:

Be it known that I, JOHN H. BURKHOLDER, citizen of the United States, residing at Ashland, in the county of Ashland and 5 State of Ohio, have invented certain new and useful Improvements in Lift-Jacks, of which the following is a specification.

This invention consists in a lift jack of new and original construction, as herein- 10 after fully described and particularly pointed out in the claims.

In the accompanying drawings, Figure 1 is a side elevation of the jack partially sectioned and showing the lift member partially raised and the handle at the limit of 15 its up stroke. Fig. 2 is a view of the jack corresponding to Fig. 1, but showing the active parts as they appear when the handle is down to the bottom of its stroke after 20 having raised the lift member one notch or tooth. Figs. 3 and 4 show views corresponding to Figs. 1 and 2 except that the lift member is being lowered and the active parts in 25 position to lower it one tooth at each stroke from the lowered position of the handle in Fig. 3 to the raised position Fig. 4. Fig. 5 is a perspective view of the inner end of the handle, Fig. 6 is a perspective view of the 30 check pawl, Fig. 7 is a perspective view of the reversing lever and Fig. 8 is a perspective view of the lift pawl and its spring. Fig. 9 is a perspective view of the upper portion of the standard.

The jack as thus shown is of the reversible 35 type, being adapted to lift and to lower an object by precisely the same movements of the operating handle and having a simple mechanism by which the change from one direction of movement to the other can be 40 instantly effected while the lift member is under a load, all as will hereinafter clearly appear.

In the drawings 2 represents the standard, which is cast to a suitable size according to 45 the work for which it is intended, say eight to twelve inches in height, rectangular in cross section, as shown herein and having a suitable base 4 to stand alone. A lift member 3 in said standard has a series of ratchet 50 teeth *a* along its inner edge adapted to be engaged by an actuating pawl 5 which is pivotally mounted on the inner end of the said handle 6 and is adapted to both raise and lower the lift member according to the 55 position of the mechanism by which the con-

version is effected. The said handle 6 is bifurcated at its inner end or has ears between which the said actuating pawl is pivoted, while a check or holding pawl 8 is mounted on the axis 9 of said handle between said 60 ears next behind pawl 5 and is adapted to engage the said ratchet teeth *a* and hold the said lift member in the interval of change by the pawl 5 from one tooth to another. A spring 10 serves to hold the pawl 8 normally 65 forward in working relation to the said lift member, but its action is modified by the effect of spring 13 of reversing lever 12 by which the actuating pawl is changed from a lift to a lowering pawl.

When lifting occurs the pawl 8 is in free 70 engaging relations with the lift member under the action of its own spring 10, and when lowering of the said member occurs the said pawl 8 is under a back pressure by 75 reversing lever 12 under the action of its spring 13. The said lever is pivoted on the axis 9 at the side of the operating handle in a swell or enlargement *c* on the rear and top of the standard and which serves as a 80 housing for all the active parts between lift member 3 and handle 6. The pivot or axis 9 is through the sides of this enlargement or housing, which has a special opening or hole *e* in its side through which the pawl 5 85 can be reached by its side pin or projection *f* and by which the said pawl can be disengaged by hand when desired regardless of the action of the other parts. The said lever 12 is seated in cavity *g* at the bottom of 90 housing *c* and engaged at its fixed end with a projection *d* on the hub of lever 12 radial at all times from axis or pivot 9 but in such relations thereto that in the lift position of the actuating pawl, Figs. 1 and 2, the spring 95 13 will exert its pressure to the outside of said axis and hold said lever retired and idle and in the lowering of the lift member it will exert its pressure on the other side of said axis and hold said member in raised 100 position to operatively engage pawl 5 as seen in Figs. 3 and 4. The said lever 12 has a handle extending out beyond the housing *c* by which one can at will throw said lever into either position across its center and the inner end thereof has a straight top engaging portion *h* and a depression or cavity *k* next thereto adapted to successively engage the said finger *f* on lift pawl 8.

The spring 13 exerts a constant upward 110

pressure and is of such strength as to overcome the action of the spring 16 of the actuating pawl and also to affect the position and action of holding pawl 8. This latter 5 action is effected by a heel portion *m* on said lever pressing against a lateral projection *n* on the pawl 8, Fig. 3, and in which position the handle 6 is depressed. When the said handle is raised and pawl 5 correspondingly 10 lowered the said projection *n* bears against the said heel *m* and depresses the inner end of lever 12 so that the finger *f* on pawl 5 will be carried back over the surface *h* into cavity *k* and thus momentarily disengage from 15 rack *a* and allow the holding pawl to come into action with the second next tooth above. This latter engagement is enforced by curved projection *b* on the lever 6 and which bears the said pawl 8 inward into such relation that as the lift member drops it will be 20 caught by said pawl. It will be understood that all these actions are momentary as the handle is operated in a pumping manner up and down.

25 The lift pawl spring 16 is supported on the pivot of said pawl and its long end bears upon the inside of lever 6 between its ears and its short end presses against a side shoulder on said pawl. This, however, is a 30 mere mechanical contrivance.

Essentially the invention resides in the means for conveniently and easily raising and lowering an object, as when engaged beneath an automobile axle, and in its 35 convenient convertibility from one use to the other. It is also seen that a single member or part serves to make the change and that in operation everything is automatic upon the operation of the handle 6. The jack is 40 also very simple in construction as practically only eleven separate parts are embodied in the complete device, all but three being primarily supported by pivot pin 9, whereby the lever operating parts may all 45 be removed or assembled with exceptional convenience and despatch, and the strain on the parts localized at this pin. The standard is also cast in one piece and is provided with ample sized openings and recesses to 50 introduce and confine the operating parts. The flaring pocket *g* particularly distinguishes this device from others in that it

affords a useful means to confine and provide a seat within which the spring 13 can be compressed and have a rocking play under the action of lever 12, and also permitting the parts to be easily assembled and taken apart in connection with pivot pin 9.

What I claim is:

1. A lift jack comprising a standard having a housing provided with a cavity at its side and bottom, a lift member slideable in said standard and having ratchet teeth at its edge, an operating handle pivoted in said housing and having a lift pawl mounted in the end thereof adapted to engage said teeth, a pin supporting said handle in said housing and a pawl mounted on said pin at the side of said handle likewise adapted to engage said lift teeth, and the said pawls arranged to act successively, a reversing lever pivoted at the side of said handle and a spring for said lever seated within said cavity, the said first named pawl having a projection at its side engaged by the end of said lever and a depression behind said end adapted to throw the said pawl out of engagement with the said lift member.

2. A lift jack comprising a standard having a housing, a lift member slideable in said standard and having ratchet teeth at its edge, an operating handle pivoted in said housing and having a lift pawl mounted in the end thereof adapted to engage said teeth, a pin supporting said handle in said housing and a pawl mounted on said pin likewise adapted to engage said lift teeth, and the said pawls arranged to act successively, a reversing lever pivoted at the side of said handle and a compression spring having an oscillatory movement and acting to hold said lever in different positions, the said first named pawl having a projection at its side engaged by the end of said lever and a depression behind said end adapted to throw the said pawl out of engagement with the said lift member.

In testimony whereof I affix my signature in presence of two witnesses.

JOHN H. BURKHOLDER.
